APPARATUS FOR THE INHALATION OF GASES

Miguel Angel Loredo Serra, Havana, Cuba

Application May 12, 1955, Serial No. 507,936

Claims priority, application Cuba May 24, 1954

3 Claims. (Cl. 128—188)

The present invention relates to an improved apparatus for the administration of no-effort anesthesia and for controlled or forced breathing of gases under pressure.

The apparatus of this invention is an improvement over the apparatus described in my U. S. Patents Nos. 2,593,774 and 2,677,371.

The object of the apparatus according to the invention is to provide a new type of breathing bag which permits the bag to instantaneously adjust itself to the breathing efforts of the user. It also comprises means for the control of forced breathing.

For the attainment of the aforementioned object the invention includes the elements and an arrangement of the same which will presently be described in connection with the annexed drawings, in which:

Figure 1 is a perspective view, with some parts broken away and others shown in section, illustrating the improved apparatus and circuit of the invention.

Figure 2 is a side elevation view of one of the tubular sections of the new breathing bag, the section being illustrated with a flexible connector attached to each of its ends.

Figure 3 is a cross section of the tubular section of Figure 2.

Figure 4 is a view similar to Figure 2 but with part of the rigid tubular body broken away to better illustrate the union of bellows located within the tubular element, and the rigid tubular body.

Hereafter, in both the specification and claims, the term "tubular breathing bag" will be used to designate the new breathing bag as a whole and said designation will include all the parts of the bag, such as the rigid tubular elements, small bellows, flexible connectors, etc. which when duly united constitute said new breathing bag.

Referring to Figure 1 of the drawing, the tubular breathing bag according to the invention comprises a series of relatively short tubular rigid members B joined end to end by short and flexible connectors C, which in the case illustrated consist of short lengths of corrugated rubber tubing which impart to the breathing bag the necessary flexibility for easy manipulation by the operator. The breathing passage or opening of the tubular breathing bag is located at A¹ intermediate the ends of a specially shaped hollow member A connected across the ends of the tubular breathing bag, but member A may have any suitable shape, and may be located at some other point of the tubular breathing bag provided it lies between the inlet and the outlet of the tubular bag, that is, between the ends of the same. Since the only purpose of the lengths of rubber tubing C is to establish a flexible connection between adjacent rigid tubes B, any other connectors may be used, provided they impart to said joints the required flexibility.

Tubular elements B constitute one of the essential parts of the tubular breathing bag, and as previously stated, they are made from rigid material in order to preserve

2

their tubular form at all times in order to allow the gas or gases to flow freely through them, while bellows B², by their ability to expand and contract, permit the tubular breathing bag to instantaneously adapt itself to the breathing efforts of the user, supplying him with the required amount of gas or gases when he inhales and easily accommodating the gases expelled by the user when exhaling. This is done with a minimum of fluctuation of the pressure within the circuit. The interior of bellows B² communicates with the external atmosphere through opening B¹ in the wall of tubular member B.

Referring to Figures 2, 3 and 4, the rigid tubular body B has an elongated opening or slot B¹ over which a wire mesh (or perforated plate) B³ is attached to the outer surface of rigid body B for preventing bellows B² from being extruded through opening B¹ when the pressure of the gases within the circuit is substantially increased. The use of slot B¹ and of mesh B³ is optional and, if desired, they may be replaced by a longitudinal series of 20 small perforations in the wall of rigid tubular member B.

The bellows extends longitudinally within tube B immediately below slot B¹, the upper edges of said bellows secured to the edges of slot B¹ and being so attached to the wall of tube B that the union between them is 25 absolutely fluid tight to prevent the gases in the circuit from escaping to the outer atmosphere and the atmospheric air from entering and mixing with the gas or gases in the circuit. In the drawing the upper edges of the bellows are shown attached to the inner surface of tube B but, if so desired, they may be brought out through slot B¹ and then attached to the outer surface of tube B.

Bellows B² projects radially into tube B a predetermined distance, and are such that when normally expanded offer the least possible resistance to the flow of 30 the gases through the tube, the bellows being fully extended when the pressure within the circuit is substantially equal to that of the external atmosphere. The bellows is of sufficient flexibility to respond immediately 35 to the smallest variation in pressure that may occur within the circuit. Any increase in the pressure of the gases within the circuit produces a proportionate contraction of the bellows until, when said pressure reaches a predetermined value, bellows B² is completely flattened 40 against the inner surface of tube B, this being the position occupied by bellows B² when the apparatus is used in the administration of forced respiration.

Due to the improvement produced in the circuit by the tubular breathing bag the apparatus may now be 45 used, not only in the administration of no-effort inhalation anesthesia, but also for controlled or forced breathing and whenever the use of gases under pressure is necessary or convenient. With forced or controlled breathing it is very convenient to include in the circuit some 50 means for controlling the pressure of the gases as desired. In Figure 1 of the drawing is shown one of the means which may be used for this purpose. It consists of a flexible bag E, made of flexible material like rubber, in communication with the circuit through which the gases 55 flow and furnished with a discharge valve F which, when open, connects the bag E with the atmosphere. Normally this valve is kept closed, being opened only when it is desired to discharge some of the gases from the circuit, for example, when after having used the apparatus to apply forced respiration it is desired to use it in the administration of no-effort inhalation anesthesia.

In order to clearly illustrate the function performed by bag E, the case in which the apparatus is used for controlled breathing will be considered. In this case 60 sufficient oxygen is introduced into the circuit by opening the corresponding valve of the oxygen supply source K until sufficient oxygen has been introduced into the

circuit to raise the pressure in the circuit to the required value. When this is done, all the bellows B^2 are flattened against the inner surface of the rigid tubes B in which they are mounted. Now, since the problem of producing controlled breathing cannot be solved by simply increasing the pressure of the gas supplied to the user, it is obvious that in order to obtain the rhythmic fluctuation in the pressure of the gas necessary for the successful application of controlled breathing, the circuit must be supplied with a suitable device easily manipulated by the anesthetist, and such a device is bag E . This bag being connected to the circuit is filled by the oxygen circulating in the circuit and the operator by successively pressing and releasing bag E causes the necessary fluctuations in the pressure of the gas applied to the patient to induce the required controlled breathing. When the operator compresses bag E in the required manner, a predetermined amount of oxygen is forced from the bag into the circuit thereby increasing the pressure in the latter, and when he frees bag E from said external pressure the bag expands and retakes from the circuit an equivalent amount of the gas. This rhythmic increasing and decreasing of the pressure within the circuit forces into and withdraws from the lungs of the patient the amount of gas required for the establishment of the so-called controlled breathing.

From the above it is obvious that bag E is not a breathing bag, but acts simply as a reservoir wherein a quantity of gas is stored when the apparatus is used with superatmospheric pressure for the purpose described in the preceding paragraph, and it can be dispensed with when the apparatus is to be used in administering no-effort inhalation anesthesia.

It is also obvious that it is not essential that reservoir E be a bag. It may have the form of a bellows with a single opening, or any other flexible gas containing device capable of expelling a portion of the gas contained therein when it is compressed and capable of recovering from the circuit an equivalent amount of gas when the applied pressure ceases.

The invention also comprises another improvement which is also important for the correct working of the apparatus.

In the circuit of the apparatus are two bellows pumps which act alternately to maintain a substantially uniform and continuous current of gases passing through a corresponding canister containing a carbon dioxide absorbing substance. By means of a suitable arrangement of valves each impeller forces the gases through its canister first in one direction and then in the opposite direction.

Referring to Figure 1 of the drawing, it is seen that the gas circulating and purifying device of the present invention comprises two separate bellows pumps Y and Y^1 , each one having a single opening located at its upper end and each being in direct communication with the interior of a canister H and H^1 respectively, which canisters contain a carbon dioxide absorbing material. Both canisters are included in the circuit and each of them communicates with the portion of the circuit through which the impure gases coming from the tubular breathing bag circulate, the communication in each instance being controlled by an inlet valve G , one for each canister, which opens to allow impure gases to penetrate into the canister when the corresponding bellows pump is being distended and so creating a vacuum which draws into the bellows the gas contained in the canister and simultaneously open valve G to admit impure gas into the canister. As soon as the bellows ceases to distend, valve G closes and no more impure gas is admitted into the canister. When the bellows commences to contract due to the pressure exerted against its lower end by a corresponding lever, pressure is applied to the gas within the bellows, this pressure is transmitted to the gas within the canister and then to outlet valve G^1 which opens and allows the purified gas to pass into that portion of the circuit through which the gases flow to-

wards the tubular breathing bag. The pumps work alternately, so that when one is performing its suction stroke the other is performing its compression stroke, whereby a substantially continuous stream of purified gas is being discharged towards the tubular breathing bag. This can be seen in Figure 1. The mechanism employed to move the pumps does not form part of the invention and, therefore, the one illustrated should not be construed as limiting the invention since it is obvious that many known mechanisms may be employed to drive the pumps alternately. Since both combinations of pump and canister are identical, it is deemed that the above description is sufficient to give a clear idea of the manner in which both work.

From the above it is seen that the new system employed in the circulation and purification of the gases in the circuit is entirely different and more efficient than those heretofore in use, not because it contains two canisters instead of one, but because due to the novel arrangement of the inlet and outlet valves, the impure gases are obliged to pass twice through the purifying medium.

In Figure 1 of the drawing the device E , which as stated before is not a breathing bag but simply a reservoir, is illustrated as located in that part of the circuit through which the purified gases flow towards the tubular breathing bag, but it is obvious that said reservoir may be located at any convenient point in the circuit.

Having thus described my invention, what I claim is:

1. In apparatus for the inhalation of gases comprising a closed circuit from which the outer atmosphere is excluded and within which the gas or gases are forced to circulate in a substantially continuous and uniform current by mechanical means included in the circuit, said circuit also including carbon dioxide absorbing means and a source of supply of the gas or gases to be inhaled, that improvement comprising a tubular breathing bag in said circuit and consisting of a plurality of rigid and relatively short tubular elements, a plurality of short and flexible connectors connecting said elements in series, each of said rigid tubular elements having a longitudinal portion of its wall perforated, a bellows within each of said rigid tubular member, said bellows being open at the top and with its upper edges hermetically attached to said rigid tubular member so that said perforation in said rigid tubular member communicates the interior of the bellows with the external atmosphere, said tubular breathing bag also including a tubular member having a breathing passage located between its ends.

2. The improvement as claimed in claim 1 in which said circuit also includes a reservoir for the gas or gases circulating in the circuit, said reservoir consisting of a hollow device with flexible walls, having a one way discharge valve.

3. The improvement as claimed in claim 1 and means for passing gases from said circuit through said carbon dioxide absorbing means, said carbon dioxide absorbing means being contained in two canisters, said means comprising two alternately acting pumps, each attached to an end of a separate canister containing carbon dioxide absorbing means, a one directional inlet valve connecting the other end of each of said canisters to the portion of the circuit through which the impure gases coming from the tubular breathing bag flow to admit said impure gases into said canister during the suction stroke of said pump, and a one way discharge valve connecting the same end of said canister with the portion of the circuit through which pure gas or gases flow towards the tubular breathing bag, whereby purified gases from said canister are discharged into said portion of the circuit during the discharge stroke of said pump.
